UNITED STATES PATENT OFFICE

149,122

DESIGN FOR AN AUTOMOBILE TAILPIPE EXTENSION

Grant M. Goodwin, San Francisco, Calif.

Application October 1, 1946, Serial No. 133,676

Term of patent 7 years

(Cl. D14—6)

To all whom it may concern:

Be it known that I, Grant M. Goodwin, a citizen of the United States of America and a resident of the city and county of San Francisco and State of California, have invented a new, original, and ornamental Design for an Automobile Tail Pipe Extension, of which the following is a specification.

Reference is had to the accompanying drawing forming part thereof, in which:

Figure 1 is a view in elevation of an automobile tail pipe extension, showing my new design;

Figure 2 is a left end elevation of the automobile tail pipe extension of Figure 1;

Figure 3 is a view in section taken along lines 3—3 of Figure 1; and

Figure 4 is a view in perspective of the automobile tail pipe extension.

I claim:

The ornamental design for an automobile tail pipe extension, substantially as shown.

GRANT M. GOODWIN.
